UNITED STATES PATENT OFFICE.

ARTHUR HALE, OF BOWLANDSVILLE, MARYLAND.

REINFORCED STOCKING.

1,106,208.

Specification of Letters Patent.

Patented Aug. 4, 1914.

Application filed November 28, 1911. Serial No. 662,884.

To all whom it may concern:

Be it known that I, ARTHUR HALE, a citizen of the United States, residing at Rowlandsburg, in the county of Cecil and State 5 of Maryland, have invented certain new and useful Improvements in Reinforced Stockings; and I do hereby declare the following to be a full, clear, and exact description of the invention, such as will enable others 10 skilled in the art to which it appertains to make and use the same.

This invention relates to stockings adapted for general use, but especially adapted for use as bathing stockings for adults, and 15 in the place of sandals or slippers for children, and has for its object to produce a foot covering of this nature that will be inexpensive and yet efficient in protecting the feet of the wearer.

20 To these ends the invention consists in the novel details of construction and combination of parts more fully hereinafter disclosed and particularly pointed out in the claims.

25 Referring to the accompanying drawings forming a part of this specification in which like numerals designate like parts in all the views:—Figure 1 is a diagrammatic view illustrating my invention when in use as a 30 bathing stocking; Fig. 2 is a like view of a detached stocking having the stiffening member partially in place; Fig. 3 is a view of a modified form of pocket for receiving the stiffening member, and showing the leg 35 portion of the stocking folded down over the foot portion; Fig. 4 is a view showing the mouth of the pocket at the toe portion of the stocking instead of at the heel portion. Fig. 5 is a sectional view of the construction shown in Fig. 4. Fig. 6 is an enlarged view of the foot portion of the stocking and showing a structure similar to that 40 illustrated in Figs. 1 and 2; Fig. 7 is a sectional view of the construction shown in Fig. 6.

45 Fig. 1 indicates the leg portion of the stocking, and 2 the foot portion thereof, which is preferably of knitted material, and of the ordinary construction. The sole of the foot portion, however, according to my invention, is

provided with two independent walls 3 and 4, forming a pocket 5 between them, into which pocket may be slipped a stiffening member or independent sole 6 to constitute a protection for the feet against stones or 55 rough objects. The inner and outer walls 3 and 4 of the sole of the stocking may be knitted integral with the foot portion 2 as illustrated.

In the form illustrated in Fig. 3, the inner 60 wall 3 terminates at or about the middle of the sole of the stocking, and the stiffening member 6 slips into the pocket as illustrated, and is left uncovered from the rear end of the inner wall 3 to the heel 7 of the 65 stocking, as will be readily understood. Fig. 4 shows a structure in which the opening 11 for the stiffening member 6 is located at the toe portion of the stocking.

In the form shown in Figs. 6 and 7, the 70 inner and outer walls of the sole portion of the stocking are the same as in the preceding figures, but the opening 10 for the stiffening member 6 is located at the heel portion 7 of the stocking, as shown. 75

It is evident that the stocking may be woven, instead of knitted, if so desired; and further, that the integrally formed sole may be made heavier by closer weaving or knitting, or by the use of heavier thread. It 80 will be further observed that in all the forms the stiffening member 6 may be readily inserted or withdrawn, for the purpose of washing the stocking, and further, the stocking may be readily turned wrong 85 side outward the same as any other stocking. It may be also worn without the stiffening member if desired. It will thus be seen that my stocking is especially adapted for bathing purposes, and for children for 90 use in the place of sandals or light slippers.

It is obvious that those skilled in the art may vary the details of construction and the arrangement of parts without departing from the spirit of my invention, and therefore I do not wish to be limited to the above disclosure, except as may be required by the claim. 95

What I claim is:—

As a new article of manufacture, a stock- 100

ing having a body portion and an inner and an outer sole portion formed integrally with said body portion, and providing a space between them conforming with the sole of 5 the foot; said sole portions having a mouth between them affording access to said space; and a sole stiffening member fitting within said space and adapted to be inserted and

removed therefrom through said mouth, substantially as described.

In testimony whereof, I affix my signature, in presence of two witnesses.

ARTHUR HALE.
